VINCENT JOSEPH MARIE ERAS, OF DORDRECHT, NETHERLANDS.

SAFETY LOCK.

Application filed December 1, 1923, Serial No. 678,010, and in Germany August 28, 1923.

My invention relates to an interchangeable safety lock for safes in safe deposit establishments, and for like purposes, said lock comprising a main or official's bolt, a secondary or renter's bolt which blocks the former bolt, both of said bolts being controlled by springless tumblers, and an auxiliary or fastening bolt for securing the lock to the posts of the safe door, or the like. The invention has for its main object to enhance the security of such a lock by improving the lock members not only of the renter's bolt, but also both of the official's bolt and the fastening bolt. Another object of the invention is to so fashion the lock that despite its minimum requirement of space, all parts of the lock will be contained in the interior of a lock casing common to said parts.

With these and other objects in view my invention consists of a novel arrangement and combination of parts as fully described in the following description and pointed out in the claims. Reference is made to the annexed drawings which show, by way of example, a preferred embodiment of my new safety lock. In the drawings:

Fig. 1 is a front view of the lock with the cover removed, the main-bolt and the secondary bolt being locked,

Fig. 2 is a similar view with the secondary bolt unlocked,

Fig. 3 is also a view similar to Fig. 1 but with both bolts unlocked,

Fig. 4 is a view in section on the line A—A of Fig. 1.

Fig. 5 is a view of the lock with the cover, the false bottom and all parts arranged at the front of the latter removed, the figure showing the slide which holds the lock-case on the posts of the door in its operating position,

Fig. 6 is a similar view but with the false bottom inserted, the slide being in its inoperative position,

Fig. 7 is a view in section on the line B—B of Fig. 6, and

Fig. 8 is a view in section on the line C—C of Fig. 5.

1 is a false-bottom fixed in the lock-case 3 by means of screws 2, 2 and stay-pins 4, 4. 5 is the main or official's bolt, and 6 the secondary or renter's bolt. The two bolts lie in one line, the secondary bolt 6 being arranged at the back of the main-bolt so that 55 the latter is blocked by the former. Consequently, at first the secondary bolt and then

the main-bolt must be moved when it is intended to open the lock. Furthermore, the lower half 6^a of the forward end of the secondary-bolt 6 projects into an angular recess 60 of the main-bolt 5 in such a manner that the corner 6^b of the bolt 6 lies in the locked position of the bolts close to the stem 18 for the key of the main-bolt. Thus the said key, when inserted through the pertaining key-hole cannot penetrate completely. The head 7 of the main-bolt 5 slides in an opening of the ledge of the lock-case, while the bolt at its rear end is guided by a pin 8 fixed to the false bottom 1 and engaging a longitudinal 70 slot in the bolt. The secondary bolt 6 is merely guided by two pins 9 and 10, the one 9 being fastened to the bottom 1, the other 10 to the back of the bolt, said pins engaging longitudinal slots in the bolt 6 and in the 75 false bottom 1, respectively. The main-bolt 5 is controlled by a set of tumblers 14 devoid of springs, only one of these tumblers being shown. The tumblers 14 are pivotally mounted on the pin 8 at their free ends they 80 are provided with a stump-slot 35 co-acting with the stump 15 of the bolt 5. The tumblers, which are held in the locked position by their own weight, are formed with two key-sweeps 16, 17 arranged at opposite sides 85 of the stem 18 so as to face each other. For setting the tumblers and simultaneously moving the main-bolt 5 a key 61 with double bit is used, the longer bit co-acting with the upper sweeps 17 and with the notch 62 of 90 the bolt 5, the shorter one with the lower sweeps 16. Thus the tumblers, by rotating the key, are always exactly adjusted to their unlocked position, lifting of any tumbler above this position is impossible even if the 95 key is rotated roughly. The key 61 is inserted through a key-hole 63 in the cover, this key-hole, which is shown by dotted lines in Fig. 1, lies parallel to the sliding direction of the bolt 5. In order to prevent the tumblers falling in front of the key-hole and consequently closing the same, which otherwise might happen if the detached lock is inverted, the stump-slots 35 of the tumblers 14 and the stump 15 of the bolt 5 are so 100 arranged with respect to each other that the stump 15 remains in the slot 35 also in the locked position of the bolt 5 so that the movements of the tumblers are limited at all events by the stump 15.

For the renter's bolt 6 there are provided by the invention two groups or sets of

tumblers 20, 21, also devoid of springs, which sets coat respectively with separate stumps 24, 25 and are designed to be commonly adjusted by a double-bitted key 64. 5 The two groups of tumblers are pivoted respectively on opposite sides of, namely above and below, the keyhole 68, which is also parallel to the direction of movement of the bolt, that is, horizontal; the said groups being respectively pivoted on pins 9, 23 secured to the bottom 1. The two groups are respectively provided with oppositely-facing key-sweeps 66, 67. The pivoting-pin 23 of the lower tumblers 21 is positioned substantially in the vertical plane of the key-pin or key-stud axis, or slightly to that side of said plane which is opposite to the pivot-pin 9 of the upper tumblers 20. Moreover, the lower tumblers 21 are provided with extensions 26 rearwardly beyond their pivotal axis, over which extensions the key-sweeps 67 are formed. The form of both groups of tumblers is so designed that they can always be returned with certainty to their arresting positions by gravity action. In order to prevent the tumblers 20, 21 from being thrown beyond their releasing positions, should the key be turned quickly, the tumblers 20 of the upper group are provided with rearward extensions or arms 27.

When the tumblers are correctly displaced, these downwardly directed arms 27 engage the rearward extensions 26 of the lower tumblers 21 and thereby limit the rotary movement of both groups of tumblers. To prevent the tumblers 21 from falling in front of and consequently closing the key-hole 68 if the detached lock is inverted, these tumblers are below the stump 25 provided 35 with a nose 69 which abuts against the stump when the position of the lock is inverted. With the upper tumblers 20 special means for this purpose are unnecessary because the movement of these tumblers is limited by their arms 27 abutting against the arms 26 of the lower tumblers 20.

As already stated, the tumblers for the main-bolt are held in their unlocked position by means of their own weight. Besides 50 this, a lever 30, 31 is provided which blocks the tumblers in the said position. The lever 30, 31 is mounted on a pivot 29 fixed to the false bottom 1. Its longer arm 30 possesses at its free end a horizontal projection or 55 finger 32 adapted to be pressed on to the upper edges of the tumblers 14 when the bolts are in the locked position. The other, shorter arm 31 of the lever rests on the upper edge of the secondary bolt 6 which is 60 provided with a recess 33 so as to form a cam-face for controlling the lever 30, 31. The bolt 6 being locked, the lever 30, 31 is held in the position shown in Fig. 1 by the upper edge of the bolt 6 in which position 65 the finger 32 presses upon the tumblers 14

so that the latter can not be lifted. By moving the bolt 6 to its unlocked position this pressure is released again so that the tumblers may be adjusted by the proper key, the lever 30, 31 being then free to turn about a 70 certain angle because the arm 31 can penetrate into the recess 33.

One or more of the tumblers of the main-bolt 5 have the inner end of the stump slot 35 provided with a recess 35^a which is so 75 shaped that the stump 15 can engage in this recess when the bolt 5 is in its unlocked position, whereby the bolt is held in this position by means of the nose 35^b formed by the recess 35^a, see dotted lines in Fig. 3. Thus, 80 on the one hand, the unlocked bolt is prevented from moving arbitrarily into the locked position, which might otherwise happen if the drawer or door is shut roughly or if the detached lock is held with the head 85 of the bolt downward. On the other hand, it is impossible now to throw both bolts forward by means of the renter's key only, on the contrary, to advance both bolts it is necessary to lift firstly the tumblers 14 90 and to shoot the main-bolt 5 by means of the official's key, whereupon the secondary bolt can be thrown forward by the renter's key. It might be possible that the tumblers 14 stick in their lifted position, so that the 95 stump 15 of the unlocked bolt 5 does not engage the recess 35^a. Nevertheless, the bolts 5 and 6 cannot be commonly shot by the renter's key, because after a slight advance of the bolts their movement is deadened by 100 the lever 30, 31 which is then blocked by the tumblers 14 resting with the noses 35^b on the stump 15.

The operation and handling of the lock above described is as follows:

In the locked position of the bolts 5 and 6 shown in Fig. 1, the main-bolt 5 is blocked by the secondary bolt 6, and the tumblers 14 of the former are secured in their locked position by the lever 30, 31, while at the 110 same time the corner 6^b of the forward end of the secondary bolt prevents the entering of the official's key. To open the lock, at first the secondary bolt 6 has to be unlocked by rotating the renter's key 64 about $\frac{3}{8}$ turn 115 (see Fig. 2), then the key remains in the lock until the bolt is shot forward again. The secondary bolt being retracted, the lever 30, 31 is free to turn, while the blocking action of the bolt 6 on the main-bolt 5 and on 120 the official's key 61 ceases. The latter key is now inserted in the key-hole 63 and it can penetrate completely so that the main-bolt 5 can also be unlocked by rotating said key a half turn. This being done, the official's 125 key may be taken out and the door of the safe can be opened.

In the locking operation the movements of the bolts are effected in a reverse order. At first the main-bolt 5 is shot forward by 130

the official's key, which then has to be withdrawn from the lock, whereupon the renter advances the secondary bolt 6 to its locked position, whereby the main-bolt is blocked 5 up again by the secondary bolt, while the tumblers 14 are again secured in their locked position so that the lock is well protected now against unauthorized opening. The secondary bolt 5 being shot forward, the 10 renter's key can also be removed.

The lock is detachably mounted on the door of the safe or the like by being hung on four posts 42, 42 which are screwed into the door. To this end the cover 80 and the 15 bottom 3^a of the lock-case 3 are both provided with four circular holes 43, 43 which allow the lock-case to slide over the posts 42, 42. To hold the lock on said posts the latter are provided with lateral notches or 20 grooves 70, while at the back of the false-bottom 1 of the lock-case 3 an auxiliary bolt or slide 40 is arranged which, with its longitudinal edges, engages the said notches 70 of the posts 42 when the slide is in its operating or fixing position, see Figs. 5 and 8. This slide is directly guided on the back side of the false-bottom 1, while at the same 25 time it is provided with stay-pins 71 bearing and sliding on the bottom 3^a of the case 30 3. Furthermore, the slide 40 possesses a puller 41 projecting out of the lock-case 3. By means of this puller the slide can be moved to its open or inoperative position shown in Fig. 6, whereby its longitudinal 35 edges become disengaged from the posts 42 so that the lock may now be taken off. Of course, at one end of the slide 40 (viz, the right end in Fig. 5) the longitudinal edges thereof must be recessed so as to form 40 passages 72 to receive the posts 42, whereas at the other end (viz, the left end in Fig. 5) of the slide is so terminated that it uncovers the openings 43 when in its inoperative position.

45 The slide 40 is secured in the fixing position by means of a lever 47 arranged in a window-like opening 46 of the slide. This lever is mounted on a pin 45 at the back of the false bottom 1, while it bears and slides 50 at the same time on the bottom 3^a of the lock case 3 by means of a stay-pin 50. The free end of the lever 47 forms a stop 73 against which a nose 51 provided at the lower edge of the opening 46 abuts, when the lever 47 55 is in the position I shown in Fig. 5, thus locking the slide 40. Furthermore, the lever 47 possesses an inclined slot 48 engaged by the pin 10 of the secondary bolt 6 already mentioned which projects through the longitudinal slot 74 in the false bottom 1. By means of this pin the lever 47 is controlled by the secondary bolt 6 in such a manner that it is held in its lowest position I when the secondary bolt 6 is locked. By retracting 60 the secondary bolt the lever is rocked 65

into its highest position II, marked by the dotted circumference of the pin 50 in Fig. 5. Also then the slide 40 is blocked against movement by the lever 47 forming now an abutment for the edge 75 of the window-like 70 opening 46. Only in an intermediate position of the secondary bolt 6 the lever 47 is at such a level (see Fig. 6) that the slide 40 does not abut against it, the slide may then be moved into its open position, shown 75 in said Fig. 6.

The lever 47 serves also for blocking or arresting the renter's bolt 6 when the fastening bolt 40 is in its inoperative position. To this end the opening 46 in the fastening bolt is made so narrow at its front end, that is, on the left of the edge 75 (Figs. 5, 6), that when the fastening bolt is withdrawn the lever 47 cannot be rotated upwardly beyond the position shown in Fig. 80 6. Hence, while the fastening bolt is inoperative, the renter's bolt cannot be wholly retracted into the lock, as is necessary in order to close the safe door. This door can be closed, on the other hand, only when the 85 fastening bolt has been shot in its operative position (Fig. 5).

Besides the lever 47, a cylinder- or barrel-lock 54 arranged at the back of the lock-casing is provided for locking the slide 40 90 in its fixing position, this cylinder-lock being, like the handle 41, accessible only after the door has been opened, the key appertaining thereto is in possession of the bank-direction. The inner cylinder 54^a of the 95 barrel-lock has an arm 55 which co-acts with a nose 56 provided on the upper edge of the opening 46 of the slide 40 in such a manner that the arm forms a stop for the slide when the inner cylinder 54^a is locked. 100 At the same time, the arm 55 serves to move the open or inoperative slide 40 back to its fixing position by rotating the said cylinder. The cylinder lock is so arranged, in a manner known per se that its key can be withdrawn only in the locking position of the 105 inner cylinder.

When it is intended to disengage the slide 40 from the posts 42, 42 the cylinder-lock 54 is firstly unlocked by inserting the pertaining key and rotating the inner cylinder 54^a $\frac{1}{4}$ turn in the direction of the arrow ω , whereupon the secondary bolt 6 is shot back half its normal path as shown by the dotted lines in Fig. 6, so that the lever 47 115 is turned into the intermediate position shown in the same figure. Then the slide 40, by means of the puller 41, is thrown into the position illustrated in Fig. 6, whereby its longitudinal edges become disengaged 120 from the posts 42 so that the lock may now be detached. Of course, before removal of the lock, the renter's key must be taken out, since its handle will not pass through the keyhole in the safe door. To this end the 125 130

secondary bolt is shot forward again, the lever 47 being thereby turned back to its lowest position, while the stop 73 enters into a recess 57 in the lower edge of the opening 46, thus holding the slide 40 in its inoperative position.

To attach the lock again to the door, the secondary bolt 6 is first thrown back half its path again. Then the lock-case 3 is slid 10 over the pivots 42, whereupon the slide 40 is moved to its operative or fixed position and blocked therein by the cylinder-lock 54 as well as by the lever 47. Should it have been forgotten to return the slide 40 to its 15 operative position, this movement is automatically effected by the arm 55 of the inner cylinder 54^a of the barrel-lock 54, when said cylinder is rotated to its locked position. As the pertaining key can only be 20 taken out after locking the cylinder-lock, it is quite impossible to leave the slide 40 in its inoperative position. By this arrangement is obtained the guarantee for the 25 banker that all the locks are fixed on the doors when he has his key from the lock.

I wish it to be stated that the invention is not restricted to the precise embodiment shown and described, for many alterations and variations may suggest themselves to 30 those skilled in the art without departing from the spirit of my invention as pointed out in the claims. Especially the new lock may not only be used in connection with safe-deposit-boxes but also for any safe-door or other door in private use where it is necessary that two persons have to control the access.

Claims:

1. A safety lock comprising in combination; a lock case, a main bolt, a secondary bolt arranged in one line with said main bolt and adapted, when locked, to block said main bolt, two horizontal keyholes in said lock case for inserting a separate key for 40 each bolt, tumblers devoid of springs for locking said main bolt, two separate sets of pivoted tumblers also devoid of springs for locking said secondary bolt, said two sets of tumblers being respectively located above 45 and below the pertaining keyhole, the pivotal axis of the lower set of tumblers being arranged substantially in the vertical plane of the latter keyhole axis, rearward extensions on the tumblers of said lower set, and 50 oppositely facing key-sweeps on said two sets of tumblers, the key-sweeps on said lower set of tumblers being formed over said rearward extensions.

2. A safety lock comprising in combination: a lock-case, a main-bolt, tumblers devoid of springs for locking said main-bolt, a secondary bolt arranged in alignment with said main-bolt and adapted, when locked, to block said main-bolt, two sets of 60 tumblers devoid of springs for locking said

secondary bolt, said two sets of tumblers being arranged opposite each other and adapted to co-act with a double-bit-key, rearward arms on said tumblers adapted to abut against each other when the tumblers 70 are unlocked, and two key-holes in said lock-case arranged parallel to the sliding direction of the said bolts.

3. A safety-lock comprising in combination: a lock-case, a main-bolt, a set of tumblers devoid of springs for locking said main-bolt, said tumblers possessing each two confronting key-sweeps adapted to co-act with a double-bit key, a stump on said main-bolt and stump-slots in said tumblers, 75 said stump and said stump-slots being so arranged with respect to each other that the stump engages said stump-slots also in the locked position of said main-bolt, a secondary bolt, arranged in one line with said main-bolt and adapted, when locked, to block said main-bolt, an upper and a lower set of tumblers for locking said secondary bolt, said two sets of tumblers being provided with confronting key-sweeps 80 adapted to co-act with a double-bit-key, rearward arms on said two sets of tumblers adapted to abut against each other when the tumblers are unlocked, an upper and a lower stump on said secondary bolt, and 85 stump slots in said two sets of tumblers, forward projecting noses on the tumblers of said lower set of tumblers, said noses being arranged below said lower stump and adapted to abut against said stump when the 90 position of the lock is reversed, and two key-holes in said lock-case arranged parallelly to the sliding direction of said bolts.

4. A safety-lock comprising in combination: a lock-case, a main-bolt, a set of tumblers devoid of springs for locking said main-bolt, a secondary bolt arranged in one line with said main-bolt and adapted, when locked, to block said main-bolt, tumblers 105 also devoid of springs for locking said secondary bolt, a double-armed blocking lever pivotally mounted in said lock-case, said lever being controlled by said secondary bolt and adapted to force said tumblers of 110 said main-bolt into their locked position and to block the same therein when the said secondary bolt is advanced.

5. A safety-lock comprising in combination: a lock-case, a main-bolt, a set of tumblers devoid of springs for locking said main-bolt, a secondary bolt arranged in one line with said main-bolt and adapted, when locked, to block said main-bolt, tumblers 120 also devoid of springs for locking said secondary bolt, a double-armed controlling lever pivotally mounted in said lock-case, a finger arranged on the forward arm of said lever above said tumblers of said main-bolt and adapted to press down said tumblers, 125 the rear arm of said controlling lever being 120

- arranged above and in the plane of said secondary bolt, the upper edge of the latter being recessed so as to form a cam-face adapted to control said lever.
6. A safety-lock comprising in combination: a lock-case, a main-bolt, a set of tumblers devoid of springs for locking said main-bolt, a stump on said main-bolt and stump-slots in said tumblers, a recess and a nose on the upper edge of the stump-slots of some of said tumblers, said recesses being adapted to be engaged by said stump when said main-bolt is in open position, a secondary bolt arranged in one line with said main-bolt and adapted, when locked, to block said main-bolt, tumblers also devoid of springs for locking said secondary bolt, a double-armed blocking lever pivotally mounted in said lock-case, a finger arranged on the forward arm of said lever above said tumblers of said main bolt and adapted to press down said tumblers, the rear arm of said controlling lever being arranged above and in the plane of said secondary bolt, the upper edge of the latter being recessed so as to form a cam-face adapted to co-act with said controlling lever.
7. A safety-lock comprising in combination: a lock-case, a main-bolt, tumblers for locking said main-bolt, a secondary bolt arranged in alignment with said main-bolt and adapted, when locked, to block said main-bolt, tumblers for locking said secondary bolt, posts for attaching the lock to the door, a slide adapted to engage said posts and to hold the lock on the same, means for blocking said slide in its operative position, said means being controlled by the said secondary bolt.
8. A safety-lock comprising in combination: a lock-case, a main-bolt, tumblers for locking said main-bolt, a secondary bolt arranged in alignment with said main-bolt and adapted, when locked, to block said main-bolt, tumblers for locking said secondary bolt, posts for attaching the lock to the door, a slide adapted to engage said posts and to hold the lock on the same, a puller on said slide projecting out of said lock-case, a lever for blocking said slide in its operative position, said lever being coupled to the said secondary bolt.
9. A safety-lock comprising in combination: a lock-case, a main-bolt, tumblers for locking said main-bolt, a secondary bolt arranged in alignment with said main-bolt and adapted, when locked, to block said main-bolt, tumblers for locking said secondary bolt, posts for attaching the lock to the door, a slide guided in the lock-case and adapted to engage said posts and to hold the lock on the same, said slide possessing a window-like opening, a lever arranged in said window-like opening and adapted to lock said slide in its operative position, said lever being coupled to said secondary bolt in such a manner that it unlocks the slide when the said secondary bolt is thrown back half its normal path.
10. A safety-lock comprising in combination: a lock-case, a main-bolt, tumblers for locking said main-bolt, a secondary bolt arranged in alignment with said main-bolt and adapted, when locked, to block said main-bolt, tumblers for locking said secondary bolt, posts for attaching the lock to the door, a slide guided in said lock-case and adapted to engage said posts and to hold the lock on the same, blocking means controlled by the said secondary bolt and a barrel- or cylinder-lock arranged at the back of said lock-casing for locking said slide in its operative position.
11. A safety-lock comprising in combination: a lock-case, a main-bolt, tumblers for locking said main-bolt, a secondary bolt arranged in alignment with said main-bolt and adapted, when locked, to block said main-bolt, tumblers for locking said secondary bolt, posts for attaching the lock to the door, a slide guided in said lock-case and adapted to engage said posts and to hold the lock on the same, a nose on said slide, a puller on said slide projecting out of said lock-case, blocking means for said slide controlled by said secondary bolt, and a barrel-lock with rotary cylinder arranged at the back of said lock-case also for locking said slide in its operative position, said rotary cylinder carrying an arm adapted to co-act with said slide nose, said arm being so arranged with respect to said nose that the said slide, when in its inoperative position, is forced into its operative position by rotating said rotary cylinder of said barrel-lock into its locked position.
12. A safety-lock comprising in combination: a lock case, a main bolt, a secondary bolt arranged in one line with said main bolt and adapted, when locked, to block said main bolt, two horizontal keyholes in said lock case for inserting a separate key for each bolt, tumblers devoid of springs for locking said main bolt, two separate sets of pivoted tumblers also devoid of springs for locking said secondary bolt, said two sets of tumblers being respectively located above and below the pertaining keyhole, the pivotal axis of the lower set of tumblers being arranged substantially in the vertical plane of the latter keyhole axis and slightly on that side of the plane which is opposite to the pivotal axis of the upper set of tumblers, rearward extensions on the tumblers of said lower set, and oppositely facing key-sweeps on said two sets of tumblers, the key-sweeps of said lower sets of tumblers being formed over said rearward extensions.
13. A safety lock comprising in combina-

tion: a lock case, a main bolt, a secondary bolt arranged in one line with said main bolt and adapted, when locked, to block said main bolt, two horizontal keyholes in said lock case for inserting a separate key for each bolt, tumblers devoid of springs for locking said main bolt, two separate sets of pivoted tumblers also devoid of springs for locking said secondary bolt, said two sets of tumblers being respectively located above and below the pertaining keyhole, the pivotal axis of the lower set of tumblers being arranged about in the vertical plane of the

latter keyhole axis, rearward extensions on the tumblers of said lower set, oppositely 15 facing key-sweeps on said two sets of tumblers the key-sweeps of said lower set of tumblers being formed over said rearward extensions, and also rearward extensions on the tumblers of said upper set, said latter 20 extensions being so arranged that they abut against the said extensions of the lower set when both sets of tumblers are unlocked.

In testimony whereof I affix my signature.

VINCENT JOSEPH MARIE ERAS.
